UNITED STATES PATENT OFFICE.

CLAUDE W. BISSELL, OF TORONTO, ONTARIO, CANADA, ASSIGNOR TO JAMES HOWARD FRANKLIN, OF WATFORD, ONTARIO, CANADA.

CAP FOR MILK BOTTLES.

Application filed June 28, 1923. Serial No. 648,338.

To all whom it may concern:

Be it known that I, CLAUDE W. BISSELL, of the city of Toronto, in the county of York, Province of Ontario, Canada, have 5 invented certain new and useful Improvements in Caps for Milk Bottles, of which the following is a specification.

This invention relates to the cardboard caps commonly used as the closures of milk 10 bottles and adapted to be pressed into the mouth of the bottle and to rest on an annular seat formed within the mouth, and my object is to devise a cap which will form as effective a closure as the present cap while 15 it is much more easily removed and replaced, and presents also three surfaces for the display of advertising matter.

I attain my object by means of the constructions hereinafter described and illustrated in the accompanying drawings in 20 which—

Fig. 1 is a plan view, on an enlarged scale, of my improved cap;

Fig. 2 a cross section on the line 2—2 in 25 Fig. 1;

Fig. 3 a similar view with the upper disk raised; and

Fig. 4 a plan view of the blank from 30 which the cap is formed.

In the drawings like numerals of reference indicate corresponding parts in the different figures.

The cap is formed of two cardboard disks 1 and 2. These may be formed of somewhat 35 lighter stock than the single disks commonly employed, so that the combined thickness of the two is about the same or not materially greater than the single ply caps. The disks are circular in form, so that the entire edge 40 of each will engage the inside of the mouth of the bottle when they are pressed into position.

While the disks may be entirely separate, they are preferably integrally united along 45 a small arc 3 of the rim of each disk. This connection being very narrow, the peripheries of the disks substantially contacting, the double disks shows little, if any, departure from a true circle, so that it will 50 perfectly fit the internal surface of the mouth of the bottle affording a tight seal.

Just in front of the integral connection of the two disks I form a hinge by means of a 55 staple 4 connecting the two disks and preferably formed of non-corrosible wire or

wire coated with a non-corrosible metal. To facilitate the swing of the upper disk 1 on this hinge, I form a line of weakness just in front of the hinge. This may be formed in various ways. I show a cut 5 formed-completely through the upper disk, which cut extends only part way towards the rim of the disk at each side, sufficient connection being left for purposes which will hereinafter appear.

Adjacent the rim of the disk 1 opposite the hinge, I form an integral tongue 6. This is preferably formed by a double cut so that the edges of the tongue are quite free of the edges of the hole, thus formed in the disk. 70 The tip 7 of the tongue is also preferably cut away to facilitate the introduction of a pointed tool beneath the tongue to raise the same.

So that the attention of the user will be 75 directed to this tongue and its function the tongue is colored to contrast strongly with the remainder of the disk and an arrow 8 is imprinted on the disk leading to this tongue.

The cap is used as follows: The milk 80 bottles are sealed with a cap in the usual manner and delivered to the user. When it is desired to open the bottle, the tongue 6 may be lifted by the use of a pointed tool or the thumb nail and used to lift the upper 85 disk. The upper disk is then pulled up and the lower disk thus withdrawn from the mouth of the milk bottle, lifting taking place, of course, at the hinge side. When the bottle is to be temporarily resealed, it is 90 merely necessary to push the disk 2 down into position, the disk 1 usually remaining partly or wholly raised.

From this it follows that both sides of the upper disk and the upper side of the 95 lower disk are seen by the user of the bottle, so that all three surfaces may be used for the display of advertising matter. Usually the upper surface of the upper disk will bear the advertising of the milk dealer, 100 while the under surface of the upper disk and the upper surface of the lower disk may be used for the advertisements of those willing to pay for the use of such an advertising medium.

The integral connection 3 between the disks has value in connection with the manufacture of the disk for the reason that it ensures that the two disks will have a fixed 105 position relative to one another, so that 110

the advertising matter on the under side of the upper disk and the upper side of the lower disk will be properly alined, so that it may be read from one position, without special care being necessary to properly position the two disks as will be the case if they were entirely separate and separately printed.

What I claim is:—

- 10 1. A bottle cup formed of two separate and similar circular disks of the same thickness and diameter, and together of substantially the same thickness as a common commercial milk bottle cap, stapled together adjacent the rim of the cap to form a hinge, an integral tongue being formed within the periphery of the upper disk diametrically opposite the hinge whereby it may be raised, and a line of weakness formed in the disk 20 adjacent the hinge and parallel thereto.
- 15 2. A bottle cap formed of two separate and similar circular disks of the same thickness and diameter, and together of substantially the same thickness as a common commercial milk bottle cap, said disks having their peripheries contacting and integrally

connected along a small arc and being stapled together adjacent the rim of the cap to form a hinge, and parallel to the chord of the arc aforesaid, an integral tongue 30 being formed within the periphery of the upper disk diametrically opposite the hinge whereby it may be raised, and a line of weakness formed in the disk adjacent the hinge and parallel thereto.

3. A bottle cap formed of two separate and similar circular disks of the same thickness and diameter, and together of substantially the same thickness as a common commercial milk bottle cap, stapled together 40 adjacent the rim of the cap to form a hinge, an integral tongue being formed within the periphery of the upper disk diametrically opposite the hinge whereby it may be raised, and a line of weakness formed in the disk 45 adjacent the hinge and parallel thereto by means of a cut severing the upper disk parallel to the hinge and of substantially the same length as the staple.

Signed at Toronto, Canada, this 26th 50 day of April 1923.

CLAUDE W. BISSELL.
